US0D1108184S

(12) **United States Design Patent** (10) **Patent No.:** **US D1,108,184 S**
(45) **Date of Patent:** **** Jan. 6, 2026**

(54) **DESK**

(71) Applicants: **Colin Andrew Dowdle**, Northfield, IL (US); **James Charles Dowdle**, Northfield, IL (US); **Curtis Leroy Cruver, IV**, Elmhurst, IL (US); **Stephen Andrew Derfiny**, Park Ridge, IL (US)

(72) Inventors: **Colin Andrew Dowdle**, Northfield, IL (US); **James Charles Dowdle**, Northfield, IL (US); **Curtis Leroy Cruver, IV**, Elmhurst, IL (US); **Stephen Andrew Derfiny**, Park Ridge, IL (US)

(73) Assignee: **LILLIPAD WORK SOLUTIONS INC.**, Greenbay, WI (US)

(**) Term: **15 Years**

(21) Appl. No.: **29/764,054**

(22) Filed: **Dec. 28, 2020**

(51) LOC (15) Cl. **06-03**

(52) U.S. Cl.

USPC **D6/656**

(57) **CLAIM**

The ornamental design for a desk, as shown and described.

DESCRIPTION

FIG. 1 illustrates a perspective view of a desk showing our new design.

FIG. 2 illustrates a front view of the desk shown in FIG. 1. FIG. 3 illustrates a rear view of the desk shown in FIG. 1. FIG. 4 illustrates a top view of the desk shown in FIG. 1. FIG. 5 illustrates a bottom view of the desk shown in FIG. 1.

FIG. 6 illustrates a left side view of the desk shown in FIG. 1; and,

FIG. 7 illustrates a right side view of the desk shown in FIG. 1.

The broken lines depict portions of the desk that form no part of the claimed design.

1 Claim, 7 Drawing Sheets
